UNITED STATES PATENT OFFICE

BENJAMIN L. FRY, OF ST. LOUIS, MISSOURI

COIN-ACTUATED MECHANISM

Application filed March 13, 1929. Serial No. 346,608.

The present invention provides a mechanism adapted for universal application to vending machines dependent upon the deposition of a coin of predetermined value into 5 a slot with which a passage connects to direct the coin to releasing means whereby vending may be consummated by manually operating a deliverer.

The invention provides a detent mechanism 10 for preventing a return of the deliverer, after an initial movement thereof in either direction, until said movement shall have been completed.

The invention, furthermore, relates to a 15 coin operated latch and a plurality of stops for preventing outward movement of the deliverer when started on its return after making delivery of the article to be dispensed, thereby compelling its complete return and 20 the depositing of another coin before the deliverer can again be moved outward.

The invention, moreover, provides a unit 25 embodying a single deliverer and two coin-controlled mechanisms adapted for independent or conjoint use accordingly as one or two coins of different denominative value are required to effect delivery of the article to be vended.

While the drawings illustrate a preferred 30 embodiment of the invention, it is to be understood that in adapting the means to meet specific needs and requirements, the design may be varied and changes in the minor details of construction may be resorted to 35 within the scope of the invention as claimed without departing from the spirit thereof.

For a full understanding of the invention 40 and the merits thereof, reference is to be had to the following description and the drawings hereto attached, in which:

Figure 1 is a longitudinal section of a 45 coin-controlled mechanism illustrative of the invention,

Fig. 2 is a horizontal section on the line 2-2 of Fig. 1,

Fig. 3 is a similar view showing a different position of the parts,

Fig. 4 is a transverse section on the line 50 4-4 of Fig. 2,

Fig. 5 is a detail perspective of the deliverer,

Fig. 6 is a detail section showing more clearly the reversible ratchet mechanism associated with the article deliverer, and 55

Fig. 7 is a detail section of the lower end of the coin tube.

Corresponding and like parts are referred to in the following description and designated in the several views of the drawings by 60 like reference characters.

The unit embodies a single article deliverer and two similar or like coin-controlled mechanisms adapted for independent or conjoint operation. The coin-controlled mechanisms are spaced apart and the article deliverer moves past them. Inasmuch as the 65 coin-controlled mechanisms are substantially alike in construction and operation with the exception that the one is right and the other 70 left, a detailed description of one will suffice for a full understanding of the structure and modus operandi.

A base plate 1 forms the bottom of an outer casing 2 and has secured thereon a floor 75 3 to support the articles 4 to be vended which are piled in a magazine having a glazed front 5. Walls 6 project upwardly from the sides of the floor 3 and are formed with grooves 7 in their inner sides to receive 80 and guide the deliverer. Coin tubes 8 are located at the rear of the floor 3 and are provided at their lower ends with lateral lugs 9 which abut the rear edge of the floor 3 and through which fastening devices are inserted 85 to secure them firmly to the floor. The coin tubes are located immediately adjacent slots 10 in the base plate 1 and the rear edges of the tubes are formed with openings 11 whereby the coins released from the tubes 90 will pass into the coin box 12 placed below the base plate and within the housing 2. As shown in Fig. 7, the outlets 11 are of such vertical extent that if a second coin be inserted before the first inserted is discharged, 95 the second coin will roll at once to the box 12 so that the attempt to improperly operate the machine will be frustrated. Across the outer side of each coin tube is an open-ended slot 13 and the inner wall of the tube is 100

formed with a grooved offset 14 mating with the slot, as shown in Fig. 4, the purpose of which will presently appear.

The deliverer 15 consists of an open frame which is closed at its bottom by the floor 3 over which it is adapted to slide, the interior of the frame coinciding approximately in form and dimensions with the articles to be dispensed, the lowermost article of the pile contained in the compartment or magazine being received within the deliverer and moved outward over the floor 3 as the deliverer is drawn forward. As the deliverer reaches the limit of its outward movement, the article contained therein clears the floor and discharges, the forward end portion of the floor being beveled downwardly, as shown at 16, and the base plate 1 being formed into a pocket or trough 17 immediately adjacent the bevel 16. An ejector plate 18 is fixed within the housing in the path of the article so that, as the deliverer is drawn forward, the article will be caused to impinge against the arcuate edge of the ejector and be thereby deflected downwardly and positively discharged from the deliverer. To accommodate the ejector, a vertically extending notch 19 is formed in the front end of the deliverer. A handle 20 projects centrally from the front end of the deliverer and is turned upwardly to project through a longitudinal slot 21 in the front projecting portion of the housing. This form of handle has been found in resist efforts to shake the deliverer in attempts to illegitimately obtain a second article. The deliverer 15 is formed with side rear extensions 22 which occupy a position over the floor 3 when the deliverer is drawn outward to the limit of its movement. A contractile spring 23 connects the deliverer with the rear portion of the housing 2, or other structure in which the mechanism may be fitted, and serves to automatically return the deliverer to normal position when released after being drawn outwardly to effect vendition, the rearward movement being limited by engagement of the front end wall of the deliverer against the front end of the magazine.

A ratchet mechanism is associated with the deliverer 15 to prevent return movement thereof in either direction when started, thereby making it necessary to complete the movement before a reverse movement may be imparted to the deliverer. This ratchet mechanism includes a rack bar 24 movable with the deliverer and an automatically reversible pawl 25 pivotally mounted above the rack and normally occupying a vertical position, as shown in Fig. 1, and held in such position by a spring 26. In the present drawings, the pawl 25 is shown as pivoted between its ends upon the side of a post or bracket 27 which is secured upon the rear end of one wall 6, and the spring 26 is disposed between and attached to the upper

end of the pawl and the upper end of the post. When the deliverer 15 has been partially drawn outwardly, the pawl 25 assumes the position indicated by full lines in Fig. 6, that is, its lower portion inclines forwardly and coats with the teeth of the rack bar 24 to prevent a return movement of the deliverer until it has completed its forward movement, at which time the pawl assumes a normal position. When the deliverer 15 reaches the limit of its outward movement, the pawl 25 clears the rack bar 24 and when the deliverer then is moved inward the pawl is reversed and assumes the position shown by dotted lines in Fig. 6. Hence, outward movement of the deliverer is prevented until it has moved completely inwardly when the pawl will clear the rack bar and assume a vertical position, as indicated in Fig. 1. The rack 24 is shown as formed on the top of one extension 22 and the front end of the rack is spaced from the front end of the extension, as shown at 28, whereby the pawl may drop from the rack and be reversed by contact with the end of the latter. Correct positioning of the unit is assured by forming slits in the walls 6 in which the lower end of the rear wall of the magazine may be engaged.

In the side of each extension 22 is a longitudinal slot 29 through which may project one arm of a latch 30, said latch being pivotally mounted on a stud 31, depending from the top of the extension, and having its inner arm normally projecting through the slot 13 in the adjacent coin tube and into the grooved offset 14 so as to block the path of the deposited coin, as indicated at 32 in Fig. 7. A spring 33 yieldably holds the latch in the described position, and in this position the end of the outer arm of the latch may abut the rear end of the wall 6 so that the forward movement of the deliverer will be prevented until the latch has been released by the deposit of the proper coin, as will be understood on reference to Fig. 2. The outward movement of the latch is limited by a stop lug 34 on the wall 6.

In the event of it being necessary to deposit two coins of different denominative value to effect dispensing of the articles to be vended, one of the coins, as a 5-cent piece, is deposited in one coin tube and the other coin, as a 10-cent piece, is deposited in the other coin tube and these coins jointly act to trip both latches so that the deliverer may be drawn outwardly and the article desired obtained. However, a single coin may be employed by removing one of the latches, said coin being deposited in the coin tube associated with the retained latch which is tripped by the coin to release the deliverer when the latter is drawn outwardly to discharge the article to be dispensed.

The normal position is shown in Fig. 2 from

an inspection of which it is evident that forward movement of the follower, if no coin is deposited, will be arrested by the latches impinging against the rear ends of the walls 6. 5 When the proper coins have been inserted, forward movement of the deliverer will cause the inner ends of the latches to impinge against the coins and, as the coins are held by the tubes against yielding, the latches will be 10 rocked to the positions shown in Fig. 3 and will clear the walls. As soon as the dogs or latches are clear of the coins, they will rock under the influence of the springs 33 so that their outer forward ends will ride along the 15 walls 6 and their opposite inner ends will be aligned with the slots 13. Then, on the return movement of the deliverer, the inner ends of the latches will enter the slots 13 and will engage the coin, if for any reason it has remained in the coin tube, and will positively 20 eject the same.

35 designates a stop rib across the front end of the floor. When a delivery is made, a second package, of course, follows the one delivered and should come to rest on the floor. If, however, the second package should tilt and tend to slide down the inclined end of the floor, the rib will arrest its progress and it will be retained until engaged and moved forward by the deliverer in the usual manner. 30

Having thus described the invention, I claim:

1. A coin-controlled unit for vending machines, the same comprising a guiding element, an article deliverer slidable along and guided by said element, a latch pivotally mounted upon and extending horizontally across the deliverer in position to impinge against the rear end of the guiding element 35 and prevent forward movement of the deliverer, and means whereby the latch may be rocked by a deposited coin to clear the guiding element and permit forward movement of the deliverer. 40

45 2. Coin-controlled mechanism including a coin-tube having an open-ended slot across one side, an article deliverer slidable past the coin-tube, a coin-tripped latch mounted on the deliverer with one end normally extending through the slot in the coin-tube to be engaged by the edge of a deposited coin and ride on the side of the coin during forward movement of the deliverer, and a stop element co-operating with the opposite end of the latch. 50

55 3. Coin-controlled mechanism including a coin-tube, a deliverer movable past the coin-tube, a latch pivoted on the deliverer and having one end normally projecting into the tube to be released by a coin therein upon movement of the deliverer to delivery position and to impinge against and eject the coin upon return movement of the deliverer, a stop to coact with the latch, and yieldable means for holding the latch in engagement with the 60 stop. 65

4. Coin-controlled mechanism including a coin-tube, a deliverer movable past the tube, means tripped by a coin in the tube to normally prevent forward movement of the deliverer, a latch pivoted on the deliverer at one side of the coin tube and having an inner arm extending across the coin tube at the rear thereof and an outer arm extending forwardly and normally engaging a fixed stop to prevent forward movement of the deliverer, the inner arm being adapted to engage a coin in the tube to be swung rearwardly and release the outer arm and permit forward movement of the deliverer, and a spring attached to the deliverer and the outer arm of the latch to return the latch to normal position upon rearward movement of the deliverer. 70

In testimony whereof I affix my signature.
